UNITED STATES PATENT OFFICE.

GILBERT AMONSEN, OF MINNEAPOLIS, MINNESOTA.

EXPLOSIVE-ENGINE.

1,318,471.

Specification of Letters Patent. Patented Oct. 14, 1919.

Application filed February 5, 1916. Serial No. 76,278.

To all whom it may concern:

Be it known that I, GILBERT AMONSEN, a citizen of the United States, residing at Minneapolis, in the county of Hennepin and State of Minnesota, have invented certain new and useful Improvements in Explosive-Engines, of which the following is a specification.

My invention relates to two-cycle horizontal explosive engines and has for its object to provide a long piston which is partly cut away at its center to allow a crank to operate between the ends of said piston and within the same. A further object is to offset both wrist pin and the crank shaft on opposite sides of the center line of the piston, so that on the compression stroke of the piston the same will be forced down against the intake port and prevent leakage of the explosive mixture. Another object is to provide a gas passageway which may have its volume changed by means of a plug screwable in and out of the same, thus varying the degree of compression. A still further object is to provide a baffle which is flush with the end of the piston and which will tend to heat the incoming gases as well as direct them away from the exhaust port.

The full objects and advantages of my invention will appear in connection with the detailed description thereof and are particularly pointed out in the claims.

In the drawings, illustrating the application of my invention in one form,—

Figure 1 is a part sectional plan view of an explosive engine embodying my invention. Fig. 2 is an enlarged longitudinal sectional view taken on line 2—2 of Fig. 1. Fig. 3 is a fragmentary cross sectional view taken on line 3—3 of Fig. 1.

In constructing my improved form of explosive engine I prefer to cast the cylinders in pairs and bolt a number of pairs together, as shown in Fig. 1, though the same may be made singly or all combined in one casting. As indicated in Figs. 1 and 3, a casting 10 provides two cylinders 11 and 12 which are separated by a wall 13 and surrounded by a water-jacket 14. The top portions of said cylinders and the water-jacket are cut away

to provide a hand hole 15, which may be closed by a cover plate 16 extending clear across all of the cylinders. A casting 17, similar to casting 10, is placed adjacent to it, and is bolted fast thereto by means of bolts 18 passing through walls 19 and 20 integral with said castings and extending up flush with the top of hand hole 15, which bolts may be inserted and applied through said hand hole. Cylinders 11, 12, etc., are of uniform bore and are open at both ends. Each pair of cylinders is closed at one end with a cylinder head 21 which has a complementary water-jacket 22 and each head covers the two corresponding cylinders and is secured thereto by means of studs 23. The other ends of the pairs of cylinders are covered by plates 24 which serve the same purpose as the heads 21 but are deprived of water-jackets.

Within the various cylinders are positioned pistons 25, 26, etc., which are identical in construction and which operate in the same manner. Fig. 2 shows the details of construction and operation of piston 25 and cylinder 12. Piston 25 is provided with rings 44 at both ends and has a portion of the top along the center thereof cut away to make room for a crank shaft 27 which passes directly through all of the cylinders. This crank shaft is positioned somewhat above the center lines of the cylinders and nearer to one end of said cylinders than to the other. One of the cranks 28 is secured to a connecting rod 29 which is pivoted to one end 30 of piston 25 by means of a wrist pin 31 in the usual manner, and said crank just clears thickened portions 46 and 47 of the piston, as seen in Fig. 3. The wrist pin 31 is below the center line of the piston, as can be clearly seen in Fig. 2. Due to this arrangement the connecting rod 29 clears the bottom of the piston and the aperture in the top of the piston may be made fairly short, thus reducing the total length of the piston.

A gas passageway 32, is located directly under the cylinder 12, passes along the same and communicates with the interior thereof at one end 33 by means of a port 34 and at the other end 35 by means of a port 36. An

exhaust port 41 somewhat in advance of port 36 passes directly out through the top of the cylinder. The chamber formed at the end 35 constitutes the explosion chamber of the engine and, as is seen, is protected by the water-jacket 22. A recess 38 in the top of the piston is provided and exposes a portion 39 of the piston head, which is perforated at 40 to act as a baffle for directing the incoming mixture away from the exhaust port 41. This baffle also serves to heat the incoming gases which are exposed to the bottom of the same as well as to the sides of the perforations 40. In running, the crank shaft rotates in the direction indicated by the arrow in Fig. 2. The operation is as follows. When the piston travels toward the explosion end of the cylinder the carbureted gas is drawn into the chamber 33 through a check valve 37 mounted on the plate 24 from a carburetor not shown in the drawings. Upon the reverse stroke of the piston the check valve 37 closes and the mixture within chamber 33 is compressed into the passageway 32 and as soon as the piston 25 passes the port 41 the burned gases within chamber 35 are allowed to discharge through the same. In this position piston 25 covers both ports 34 and 36 and so prevents any possible occurrence of backfire. When the piston then uncovers port 36 the fresh mixture rushes into chamber 35 in the usual manner, expelling nearly all the foul gases. Further movement of the piston compresses the gas in the explosion chamber which is ignited in the usual manner by a spark plug 45. It will here be noted that as the crank 28 travels through the compression stroke, the piston 25 is forced downward against the port 36 through the vertical component of force procured by offsetting the crank shaft and wrist pin from the center line of the piston, thus preventing leakage and insuring a sufficient degree of compression.

Passageway 32 communicates, as shown in Fig. 2, with a downwardly-extended bore 42 which is internally threaded to receive a plug 43. By screwing said plug into or out of the bore 42 the volume of the combined passageway can be varied to secure any degree of compression desired.

The manner of journaling the crank shaft is best seen in Figs. 1 and 3. A pair of bosses 48 and 49 are cast integral with the outer sides of the cylinder castings 11 and 17, and carry bearing bushings 50 which support the crank shaft at the two ends. A central bearing bushing 51 supports the crank shaft at the center and is carried by two complementary bearing members 52 and 53. Members 52 and 53 are held in place between the walls 19 and 20 of castings 11

and 17 by means of plates 54 and 55 cast integral therewith, through which the bolts 65 18 pass. By this means this bearing can be easily aligned and is furthermore rigidly supported.

For the purpose of assembling, a slot 68 is formed in each of the side walls 19 and 20 of the castings 10 and 17, through which the crank shaft may be inserted. The crank shaft 27 has attached to it at one end a fly wheel 56, as is customary with most engines. Feet 57 may be cast with the cylinders for supporting the engine and for securing the same to some suitable base.

The advantages of my invention are manifest. With the cover plate and hand hole positioned on the engine as shown all parts 80 of the engine become accessible from the top and the removal or substitution of parts becomes very simple. The piston proper may be used as an oil reservoir and thus all of the working parts may be kept well oiled without the use of an auxiliary oiling system. The compression in the intake end of the cylinder serves as a cushion for the piston and helps to return it to its opposite end.

I claim:

1. A two cycle explosive engine comprising a horizontal cylinder having a port in the bottom thereof, a piston within the cylinder adapted to cover said port throughout the greater portion of its compression 95 stroke and to remain seated over said port throughout the greater portion of its explosion stroke through its own weight, and a crank having its axial center above the axis of said piston, and a pitman connected 100 to the piston below the axis thereof to cause the piston to bear down upon the lower portion of the cylinder about said port in excess of its weight during the compression stroke.

2. A two-cycle explosive engine comprising a horizontal cylinder, a double-ended piston in said cylinder of such length as to provide chambers at the ends of the piston, the one being a pumping chamber and the other an explosion chamber, a crank shaft 11 having operative connection with said piston between the ends thereof, a charging chamber having port connections with the pumping chamber and with the explosion chamber, the opening of said ports being 11 controlled by the piston, a valve for admitting explosive mixture into the pumping chamber, and means for varying the capacity of the charging chamber.

3. A two-cycle explosive engine comprising a horizontal cylinder, a double-ended piston in said cylinder of such length as to provide chambers at the ends of the piston, the one being a pumping chamber and the other an explosion chamber, a crank shaft 12 having operative connection with said pis-

ton between the ends thereof, a charging chamber having port connections with the pumping chamber and with the explosion chamber, the opening of said ports being controlled by the piston, a valve for admitting explosive mixture into the pumping chamber, said charging chamber including a threaded cavity fitted with a screw plug

for varying at will the capacity of the charging chamber.

In testimony whereof I affix my signature in presence of two witnesses.

GILBERT AMONSEN.
